UNITED STATES PATENT OFFICE.

LEON TULEIKIS AND JOSEPH COLLINS, OF PHILADELPHIA, PENNSYLVANIA.

WINDOW CONSTRUCTION.

Application filed January 7, 1927. Serial No. 159,674.

Our invention relates to new and useful improvements in a window construction, and has for its primary object to provide means for attachment to an ordinary window of usual construction to permit of swinging the lower or both sash inward relative to a building, of which they form a part, on a horizontal line whereby the outer surfaces of said sash will be accessible from the inside of the building.

Another object of the invention is to provide hinged guide plate portions with their associated sash guides so that said guide plate portions may be swung outward from the window frame to permit access to both sides of one or both sash from one side of the window frame.

The invention consists essentially of forming the guide plates into upper and lower portions and hinging the upper portions to said lower portions, whereby said upper portions may be swung out of the window frame, carrying with them whatever number of sash may be within said upper portions. It is to be understood that the upper portions of the guide plate only are hinged to the lower portions thereof for the purposes set forth in contradistinction to the structure illustrated and described in our companion case filed on even date herewith.

With these and other ends in view, this invention consists in the details of construction and combination of elements herein-after set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1, is a front elevation of a window and its component parts constructed in accordance with our invention, all of the parts being shown in their closed positions, and a portion of the window frame, or one of the sash weight boxes being broken away to illustrate details of construction.

Fig. 2, is a perspective view thereof with both sash in the upper portions of the guide plates, and said upper portions swung out of the window frame, or inward relative to a building, so that access may be readily had

to the outer surface of one of the window sash.

Fig. 3, is an enlarged fragmentary sectional view on the line 3—3 of Fig. 1, with the upper portions of the guide plates in an open position and both sash therein.

Fig. 4, is an enlarged fragmentary section on the line 4—4 of Fig. 1, showing the upper sash in the lower portions of the guide plates and the lower sash in the upper portions of said guide plates which are in an open position.

Fig. 5, is an enlarged front elevation of the sash cord guide pulleys.

In carrying out our invention as herein embodied, 6 represents the usual window frame mounted in the wall of a building and including the sash weight boxes 7. The sash weight boxes are constructed in the usual manner and include the facing boards 8 usually carrying the strips or beads 9 to form the guide-ways for the window sash 10 and 11, the sash 10 being the lower one and the sash 11 being the upper one.

The ordinary beads or strips 9 referred to above are usually all removed, but if found desirable the one adjacent the outer face of the window may remain in place, as shown in Figs. 3 and 4.

To apply our invention, both window sash are removed from the frame and, if necessary, the sides thereof are planed or otherwise reduced in width in order to insert the guide plates, to be presently described, and while out of the frame, said window sash are grooved along their side edges throughout their entire length, or from their upper ends to points adjacent the lower ends, said grooves being shown at 12 in Figs. 3 and 4.

On the outer surfaces of the facing boards 8 at their lower ends are mounted the lower portions of the guide plates 14, where said portions are permanently held by any suitable fastening means, and said lower guide plate portions are provided with ribs or beads 15 suitably spaced to provide guide-ways for both window sash. The lower portions of the guide plates extend upwardly from the bottom of the window frame to points adjacent the upper end of the lower window sash or adjacent the meeting rails of both window sash. Above these points are mounted the upper portions of the guide plates 16 which are similar in all respects

to the lower portions and include the spaced longitudinal ribs or beads 17 to provide guideways for the window sash. The lower ends of the upper portions of the guide plates are hinged at one edge to the upper ends of the lower guide plate portions at one edge, the hinges being shown at 18.

While it is preferable, that the guide plate portions be hinged at their inner edges, or at the edges facing the inside of the building, we do not wish to be limited to such an arrangement, as under some conditions, it might be well to hinge the parts together at their outer edges.

Within the sash weight boxes are located the sash weights 19 connected to the inner ends of the sash cords 20 passing over pulleys 21 at the top of the sash weight boxes, and mounted on the inner surfaces of the facing boards the opposite ends of said sash cords 20, passing between the pairs of co-operating guide pulleys 22, 22', journaled in suitable bearing plates 23, the latter being mounted on the inner surfaces of the facing boards or the inner surfaces of the stationary lower portions of the guide plates. In the bearing plates 23 are also journaled buffer rolls 24 at right angles to the co-operating guide pulleys and are so located relative to said guide pulleys as to prevent the sash cords being pulled out of said guide pulleys when the sash are swung outward, as will be obvious by reference to Fig. 4. The sash cords 20 are passable into the grooves 12 at the sides of the lower sash, and have their ends fixed adjacent the lower end of said sash.

The sash weights 25 are attached to the inner ends of the sash cords 26 which pass over pulleys 27 at the top of the window frame, and then downward and between the guide pulleys 22, 22' of a set similar to the first mentioned ones, the opposite ends of said sash ends 26 being fixed to the lower end of the upper sash within its grooves 12.

In order to maintain the upper portions of the guide plates in a closed position, as shown in Fig. 1, suitable spring actuated latches 28 are mounted on the said upper portions of the guide plates with the bolts of said latches engaging keeper apertures in the window frame, and in order to conveniently operate said latches, the upper ends of rods 29 are pivoted to the operating mechanism or bolts of the latches. Said operating rods are also used for supporting the upper portions of the guide plates with the sash therein in inclined open position, as shown in Fig. 2 by placing the free ends of the rods against some suitable part of the window frame.

When it is desired to clean the outer surfaces of the window panes or the exposed portions of the frame work of both sash, the lower window sash may be raised so

that both sash are in the upper portions of the guide plates, then by pulling upon the operating rods 29, the bolts of the latches 28 will be withdrawn from their keepers, and said upper portions of the guide plates may be opened because of their hinged connections with the lower portions of said guide plates, as shown in Fig. 2, and said upper portions of the guide plates with both sash therein may be supported in the inclined position by the rods 29. While in this position the outer surface of the upper window frame and the outer exposed surface of the window frame work may be cleaned, or other work done thereon, after which the upper portions of the guide plates are returned to their closed positions, and the upper sash moved down into the lower portions of the guide plates. The upper portions of the guide plates are then again opened exposing the outer surface of the lower sash so that it may be worked upon the same as the upper sash. After the cleaning or other operations have been completed, the upper portions of the guide plates are finally moved into their closed position where they will be held by the spring actuated latches 28, and both window sash may then be raised or lowered in the usual manner.

While it does not seem to be absolutely necessary, we believe it advisable to brace the outer free ends of the guide plates by cross strips 30 to prevent said guide plates from spreading apart.

When the upper portions of the guide plates are moved into their open position, as shown in Fig. 2, the window sash may be readily removed therefrom by pulling said sash downward and loosening or unhooking the sash cords. Such an arrangement also makes it easy to replace worn or broken sash cords with new ones. In order to prevent accidental sliding of the sash from the guide plates, a latch 31 may be placed on one side of each sash, so as to engage the guide plate portions, thus securely locking the sash in place.

By providing a window construction as herein described, both window sash may be swung into a building, and any desirable operations carried out thereon while inside of the building, thereby eliminating the necessity of sitting on a window sill or using a support on the outside of the building to do any work whatever on the outer surfaces of either window sash.

It will be readily noticeable that the operating rods 29 may be used for supporting curtains, draperies or other objects, thus making it unnecessary to use the ordinary curtain rods or brackets.

Where it is desirable to use separate curtain or shade brackets these may be properly positioned under the spring actuated latches 28 at right angles to said latches.

Of course we do not wish to be limited to the exact details of construction as herein shown as these may be varied within the limits of the appended claims without departing from the spirit of our invention.

Having thus fully described our invention, what we claim as new and useful is:

1. A window construction comprising a window frame including sash weight boxes, lower portions of guide plates fixed within the frame, upper portions of guide plates hinged to the upper ends of the lower portions so as to swing relative to said lower portions, while remaining parallel to each other, sash slidably mounted between the guide plates, guide pulleys arranged in co-operating pairs and mounted on the inside of the sash boxes adjacent the point of meeting of the pair of sash, buffer rolls associated with the guide pulleys with their axes at right angles to the axes of the guide pulleys, other pulleys within the sash weight boxes at their upper ends, sash cords passing over said other pulleys and other guide pulleys and having ends connected with the lower ends of the sash, weights on the opposite ends of said cords, and means to temporarily maintain the upper portions of the guide plates within the window frame.
2. The structure set forth in claim 1 wherein the means for holding the upper portions of the guide plates within the window frame consists of spring-actuated latches and operating rods connected with said latches and depending to a position within easy access of an operator, said rods engaging the lower portion of the window frame to hold the upper portions of the guide plates in an inclined position.
3. A window construction comprising a window frame including sash weight boxes, lower portions of guide plates fixed within the lower part of the window frame, upper portions of guide plates, means to hinge the lower ends of the upper portions to the upper ends of the lower portions whereby said upper portions may be swung into or out of the window frame parallel with each other, beads carried by the guide plates, window sash slidably mounted in the guide plates between the beads and when within the confines of the upper portions of the guide plates to be moved therewith, pulleys adjacent the upper ends of the window frame and within the sash weight boxes, guide pulleys mounted on the inside of the sash weight boxes adjacent the meeting point of the sash, buffer rolls associated with said guide pulleys at right angles thereto and located on those sides of the guide pulleys facing toward the hinged points of the guide plates, sash cords connected with the lower ends of the sash and passing through the guide pulleys and over the other pulleys, said cords adapted to engage the buffer rolls when the sash are open, weights on the opposite ends of said sash cords, spring-actuated latches mounted on the upper ends of the guide plates, the bolts of said latches adapted to register with recesses in the window frame, and operating rods for actuating said latches and said rods engaging the lower part of the window frame when the upper portions of said guide plates are opened in order to support said upper portions in inclined positions.
4. The structure set forth in claim 3 wherein the upper portions of the guide plates are at least equal to the length of the longer sash, while the lower portions are at least equal to the length of the shorter sash.

In testimony whereof, we have hereunto affixed our signatures.

LEON TULEIKIS.
JOSEPH COLLINS.
